UNITED STATES PATENT OFFICE.

IRVIN B. SAWYER AND THOMAS CLARK, OF QUINCY, ILLINOIS.

SOFT-COAL COOK STOVE AND RANGE.

SPECIFICATION forming part of Letters Patent No. 308,864, dated December 2, 1884.

Application filed March 17, 1884. (No model.)

To all whom it may concern:

Be it known that we, IRVIN B. SAWYER and THOMAS CLARK, citizens of the United States, residing at Quincy, in the county of Adams 5 and State of Illinois, have invented a new and useful Improvement in Soft-Coal Cook Stoves and Ranges, of which the following is a specification.

Our invention relates to improvements in 10 soft-coal cook stoves and ranges; and the objects of our improvements are, first, to heat the front, bottom, and back plates of the oven with hot air in conjunction with the direct heat from the fire passing over the top of the 15 oven; second, to afford facilities for the distribution of the direct heat from the fire equally over the top of the oven and under the top plate of the stove or range. We attain these objects by the arrangements illustrated 20 in the accompanying drawings, in which—

Figure 1 is a longitudinal section of the stove, taken vertically on the line $y y$ of Fig. 2. Fig. 2 is a plan view of the stove with the 25 top plate of the stove removed. Fig. 3 is a plan. Fig. 4 is a side view of the stove. Fig. 5 is a section on line 1 1 of Fig. 1. Fig. 6 is a section on line $x x$ of Fig. 1.

Similar letters refer to similar parts throughout the several views.

On the top plate, B, is placed the elevated flue A, as shown.

C C are vertical partitions between the top plate, B, and the top plate of the oven O, 35 forming three flues, S S S, over the oven O for the passage of the direct fire-heat, as indicated by the arrows b b. The center flue S discharges through the hole K in the top plate, B, into the flue-box A, thence by the pipe-exit 40 P to chimney.

D D D are dampers secured to a rod passing through the plates C C, as shown, for the purpose of regulating the direct draft. The center damper is fixed at right angles to the 45 two side dampers.

E E are two vertical curved plates at the rear end of the two outside flues, S S. These plates are joined to the two side plates, N N, and are separated opposite the center flue S, leaving 50 a passage for the hot air from the chamber H

to form a junction with the direct center flue S. F is the fire-box, and G the grate.

H' H', Fig. 4, (shown by dotted lines,) is the flue for the entrance of cold air, which passes to the chambers H H, Fig. 5, at the ends of 55 the fire-box F. The air, becoming partially hot, passes to the chamber H², Fig. 1, at the rear of the fire-box F; thence, becoming thoroughly hot, it passes through the opening in the plate M, Figs. 1 and 5, to the chamber H³, 60 Fig. 1, at the bottom of the oven O; thence through the chamber H⁴, at the rear of the oven O, it passes between the plates E E, and forms a junction with the direct heat from the fire, producing a more perfect combustion. 65

I, Figs. 1 and 2, is an outer air-chamber for the more perfect protection from outside temperature of the hot-air chamber H around the oven O.

L is an interposed shell between the hot-air 70 chamber H³ and the chamber I, and J is the ash-box.

N are the side and bottom plates of the 75 stove or range, and P is the exit-pipe for smoke.

The arrows indicated by the letter a show the direction of the hot-air around the fire-box F and oven O, and those indicated by the letter b show the passage of the direct fire heat.

Heretofore cooking-stoves adapted to burn 80 soft coal have generally been so constructed that the products of combustion were carried around the oven through various flues to heat the same, thereby causing an accumulation of soot in the flues, which in time prevent the 85 passage of the heat by blocking the flues. This soot was liable to be fired by the sparks and flame from the fire-box.

It has been suggested to form a chamber about the fire-box with openings to the outer 90 air for the admission of fresh air, and provided with channels leading under the oven and behind the same, connected with this chamber, to heat the oven by hot air, the products of combustion passing over the top plate of the 95 oven to the rear where the exit-pipe was located, and where it met with the current of heated air rising from the flue at the rear of the oven. This arrangement was quite as objectionable as the old form, as the heavy pro- 100

ducts of combustion would, after being deflected against the rear wall of the stove, fall to the bottom of the rear flue, and in a very short time accumulate soot and ashes to such an extent in the bottom of the flue as to stop the proper circulation of the hot air.

Our invention is designed to overcome these objections and difficulties by carrying the products of combustion to the exit-pipe without coming in contact with the rear wall of the stove, and without crossing any of the hot-air flues, and by heating the front, bottom, and back of the oven by heated air from a heating-chamber around the fire-box.

15 Our next improvement consists in the arrangement of the flues over the top oven-plate, which are three in number. The direct heat from the fire passes along each side to the center flue, where a junction is formed with the hot air from the rear plate of the oven, and is returned through the center flue to find its exit through the flue-box on top of the stove or range. By this arrangement we get an equal division of the direct fire heat over the top oven-plate, and also an equal draft on the fire, the result of which is the coal is consumed equally as readily at the sides as at the center of the fire-box, by which the durability of the fire-plates are enhanced as well as the heat more equally distributed. By the flue-box on top of the stove or range we not only get an equal division of the flues below, but obtain a direct upward draft to the discharge-pipe, thence to chimney. We also by this device retain the 35 middle back pot hole or opening in an elevated position, rendering it much more convenient for use than when placed on a level with the other openings. The hot-air chamber around the bottom and rear end of the oven is protected from outside temperature by an outer 40 air-chamber.

Having fully described our invention, what we desire to claim and secure by Letters Patent is—

1. In a stove, the combination of a hot-air chamber surrounding the fire-box, passages leading therefrom forming a continuous flue for the hot air around the front, bottom, back, and top of the oven, an exit-flue arranged directly above the oven and out of direct line with the hot-air flue at the back, and a flue or flues from the fire-box to said exit-pipe, whereby the products of combustion pass to the exit-pipe without crossing the hot-air-flue openings, substantially as described, and for 55 the purpose set forth.

2. In a stove, the combination of a hot-air chamber surrounding the fire-box, passages leading therefrom forming a continuous flue for the hot air around the front, bottom, back, and top of the oven, and an exit-flue arranged directly above the oven and out of direct line with the hot-air flue at the back, with flues for the products of combustion arranged upon the top plate of the stove formed with the walls 60 C C and having the dampers, whereby a direct or indirect draft is obtained by the movement of one lever, substantially as described.

3. In a stove of substantially the form described, the combination, with the exit-flue arranged above the oven and out of direct line with the hot-air flue at the back, of the flues for the products of combustion, the walls C C, dampers D D, and the deflecting-plates E E, all substantially as described, and for the purpose set forth.

IRVIN B. SAWYER.
THOMAS CLARK.
